UNITED STATES PATENT OFFICE.

ROY S. DURSTINE, OF SCARSDALE, NEW YORK, ASSIGNOR TO LEVER BROTHERS COMPANY, OF CAMBRIDGE, MASSACHUSETTS, A CORPORATION OF MAINE.

DESIGN FOR A CAKE OF SOAP OR SIMILAR ARTICLE.

Application filed April 2, 1925. Serial No. 12,982. Term of patent 14 years.

To all whom it may concern:

Be it known that I, ROY S. DURSTINE, a citizen of the United States, and a resident of Scarsdale, in the county of Westchester and State of New York, have invented a new, original, and ornamental Design for a Cake of Soap or Similar Article, of which the following is a specification, reference being had to the accompanying drawings, forming a part thereof, and in which—

Fig. 1 is a plan view, and
Fig. 2 is a side elevation of a cake of soap embodying my design.

I claim:

The ornamental design for a cake of soap or similar article, as shown.

ROY S. DURSTINE.
